COIN-FREED POWER VENDING APPARATUS

Paul Moos, Zug, Switzerland, assignor to Landis & Gyr, A.-G., a corporation of Switzerland

Application December 28, 1934, Serial No. 759,485
In Switzerland February 2, 1934

13 Claims.

(Cl. 194—3)

The invention relates to improvements in coin-freed vending apparatus, and more particularly to novel and useful improvements in coin-controlled electricity metering devices.

5 Objects and advantages of the invention will be set forth in part hereinafter and in part will be obvious herefrom, or may be learned by practice with the invention, the same being realized and attained by means of the instrumentalities and combinations pointed out in the appended 10 claims.

10 The invention consists in the novel parts, constructions, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Fig. 1 is an elevation of a mechanism embodying the invention; and

Fig. 2 is a vertical section showing the details of the escapement mechanism.

25 An object of the present invention is to provide improved power vending mechanism capacitated to dispense power on a combined or concurrently registering time rate and power consumption rate. A further object is to provide an efficient and simplified mechanism in which complicated and expensive mechanisms are not required, and which avoids undesirable and heavy stresses and heavy wear of the parts due to excessive movement and/or impact between 30 parts of the mechanism. The invention further provides a coin controlled vending apparatus which registers the basic charge resulting from progressing the switch controlling mechanism under the action of the time mechanism, the apparatus comprising a power storing and driving means acting on the switch controlling mechanism, said action being regulated and controlled by a time mechanism. Other objects and features of the invention will be described in connection with the following detailed description.

35 Referring now to the exemplary embodiment of the invention illustrated in the accompanying drawing, a meter disc 1 is mounted on a spindle 2 which rotates in bearings 3 and 4. The spindle 2, through gearing 5 drives shaft 6, which through gears 7 drives shaft 8. From shaft 8 a train of gearing 9 connects to a suitable registering device 10.

40 A suitable coin controlled mechanism is provided, and a shaft 21 is freed for a predetermined

amount of rotation by the deposit of a coin in the usual manner. In the embodied means for moving back the connections to the meter to represent the corresponding customer credit, through gears 22 and 23 and arms 24 and 25, shaft 21 rotates shaft 26. Fixed on shaft 26 is a gear 27 which meshes with a gear 28, journaled loosely on shaft 29. Integral with gear 28 is a sun wheel 30, of a planetary gear. The other sun wheel 31 is integral with a gear wheel 32, both being freely journaled on shaft 29. Gear wheel 32 meshes with a gear wheel 33, which is integral with pinion 7 on shaft 8. Planet wheel 34 is journaled on arm 35 fixed to rotate with shaft 29. Thus the planetary gear is rotated in one direction by the coin-release mechanism proportional to the customer credit created, and in the opposite direction by the meter disc 1 during the current consumption.

45 Referring now to the connections from the foregoing mechanism for operating and controlling the switch controlling mechanism, a gear 41 is fixed on shaft 29, and meshes with a gear 42 fixed on shaft 43. Fixed to the hub of gear 42 is a radially extending and angled arm 44 having 50 fixed thereto a detent tooth 45. Loosely sleeved on shaft 43 are a pair of escapement gears 47 and 48, which are fixed together and are offset angularly half the pitch of their teeth to effect an escapement action with the detent 45. Fixed 55 to the gears 47 and 48 to rotate therewith are two broad faced pinions 53 and 54, and fixed to these are a grooved and flanged wheel 55; the escapement wheels, the broad faced pinions and the grooved wheel being integral and rotating 60 freely together on shaft 43. The connections from the aforesaid mechanism to the setting mechanism comprises a shaft 59, journaled in the frame and having one end journaled loosely in the hub of gear wheel 41. Fixed on shaft 59 65 is a gear 60, which meshes with broad faced pinion 53 and fixed on the other end of shaft 59 is an arm 61. Arm 61 co-acts with bent arm 62 on shaft 63 of the switch controlling mechanism. By this mechanism arm 62 and shaft 70 75 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

46 In the embodied form of time-controlled drive for the escapement mechanism just described, a shaft 68 driven from the time mechanism, 55

drives through worm gear 69 a vertically-disposed shaft 70. The lower end of shaft 70 projects into the groove in the wheel 55 and is offset to give a crank motion, so that as the shaft 70 is rotated by the time mechanism, the grooved wheel 55, the broad faced pinions and the escapement wheels are reciprocated on their shaft, and by reason of the offset of the wheels by one-half of the tooth pitch, an escapement action 10 is effected in conjunction with detent 45. As shaft 43 is driven from the disc 1, arm 44 and detent 45 rotate about shaft 43, advancing the wheels correspondingly to the power consumed, and the rotation of shaft 70 operates the escapement, the total advance of the wheels 47, 48 and pinions 53, 54 being the sum of both these drives.

In accordance with one feature of the invention, driving means are provided for imposing a 20 resilient or yielding forward drive on the wheels 47, 48 and pinions 53, 54 whereby they move forwardly under the concurrent drive of the meter disc and under the control of the time mechanism, said driving means being independent 25 of the time mechanism. As embodied, the driving means comprises a helical spring 76 which is connected to a toothed sector 77. Sector 77 meshes with a pinion 78 fixed on a shaft 79, and a gear wheel 80 is fixed on the shaft 79 30 and meshes with the broad pinion 54 to communicate the drive from spring 76 to the escapement mechanism, the group of mechanism which includes arm 44, gears 47, 48 and pinions 53, 54 acting to control the spring drive in accordance with the movement of disc 1 and the time mechanism 68.

Means are provided for counting the total 40 number of coins deposited, and as embodied, a bevel gear 83 is fixed on the hub of gear 28, and meshes with a bevel gear 84, which is part 45 of the coin-counting mechanism. An indicating device to show customer credit for coins deposited and customer debit on the time basis charge is provided, this mechanism including an indicator 85 driven through gearing 87 from bevel gear 88 fixed on shaft 79.

The manner of operation is as follows:—When 50 a coin is inserted and shaft 21 is correspondingly rotated, through gears 22, 23 shaft 26, gears 27, 28, sun wheel 30 rolls planet wheel 34 a corresponding distance on sun wheel 31, whereby 55 through shaft 29 and intervening connections, arm 44 and detent 45 rotate escapement wheels 47, 48 and pinions 53 and 54 backwardly a distance corresponding to the customer credit 60 created by the coin deposited. At the same time through gear 60 and connections, including arms 61 and 62, setting mechanism 63 is correspondingly moved backwardly and the switch is closed. Also at the same time, through the gear connections, driving spring 76 is wound.

The meter disc 1 now drives sun wheel 31, which causes planet wheel 34 to roll on sun 65 wheel 30, shaft 29 rotating therewith, and moving in the opposite direction from the previously described movement imparted by the deposit of the coin. Gear 41 on shaft 29, drives gear 42 and rotates arm 44 and therewith gears 47, 48 and pinions 53 and 54 proportionately to the 70 movement of disc 1. From these, through the connections already described, the setting mechanism also advances correspondingly to the power consumption.

At the same time, the time mechanism rotates 75 shaft 68, which reciprocates the gears 47 and 48

relatively to the detent 45 to effect an escapement movement. The advance movement of the mechanism is thus the sum of the drive of the meter disc 1 and of the advance permitted by the time mechanism, and corresponds to the power consumption plus the basic time charge. When the current consumption equals the value of the deposited coin the setting mechanism will release the switch and cut off the current. The time mechanism, however, continues to operate, 10 and the basic charge will be recorded as a customer debit by the register 86.

The invention in its broader aspects is not limited to the specific mechanisms shown and described but departures may be made therefrom within the scope of the accompanying claims without departing from the principles of the invention and without sacrificing its chief advantages.

What I claim is:

1. A prepayment meter mechanism having coin controlled mechanism and a time mechanism, in combination power line switch controlling means, a meter, a gear train between the meter and said switch controlling means, power means for driving said gear train, an escapement mechanism in said gear train, and connections from the time mechanism for actuating said escapement mechanism.

2. A prepayment meter mechanism having coin controlled mechanism and a time mechanism, in combination power line switch controlling means, a meter, a gear train between the meter and said switch controlling means, means connected to said gear train and acting to impel the gear train and controlling means toward switch opening position, an escapement mechanism in said gear train, and connections from the time mechanism for actuating said escapement mechanism.

3. A prepayment meter mechanism having coin controlled mechanism and a time mechanism, in combination power line switch controlling means, a meter, a gear train between the meter and said switch controlling means, an escapement mechanism in said gear train, spring driven means acting on said gear train between said escapement mechanism and said switch controlling means, and connections from the time mechanism for actuating said escapement mechanism.

4. A prepayment meter mechanism having coin controlled mechanism and a time mechanism, in combination power line switch controlling means, a meter, a gear train between said meter and switch controlling means, power means for driving said gear train including a differential gear with one side in said train, gear connections from the coin controlled mechanism to the other side of said differential gear, and an escapement mechanism in said gear train between said differential gear and switch controlling means and controlled by the time mechanism.

5. A prepayment meter mechanism having coin controlled mechanism and a time mechanism, in combination power line switch controlling means, a meter, a gear train between said meter and switch controlling means, including a differential gear with one side in said train, gear connections from the coin controlled mechanism to the other side of said differential gear, an escapement mechanism in said gear train between said differential gear and switch controlling means, and spring driven means connected to said gear train between said differential gear and switch controlling means impelling the gear train and

controlling means toward switch opening position.

6. A prepayment meter mechanism having coin controlled mechanism and a time mechanism, in combination power line switch controlling means, a meter, a gear train between said meter and switch controlling means, including a differential gear, and an escapement mechanism in said gear train between said differential gear and switch controlling means and controlled by the time mechanism.

7. A prepayment meter mechanism having coin controlled mechanism and a time mechanism, in combination power line switch controlling means, a meter, a gear train between said meter and switch controlling means, including a differential gear with one side in said train, gear connections from the coin controlled mechanism to the other side of said differential, an escapement mechanism in said gear train between said differential and switch closing means, connections from the time mechanism for actuating said escapement mechanism, and a driving spring and gearing connected to said gear train between said escapement and switch controlling mechanism.

8. A prepayment meter mechanism having coin controlled mechanism and a time mechanism, in combination power line switch controlling means, a meter, a gear train between said meter and switch controlling means, power means for driving said gear train, an escapement mechanism in said gear train comprising a double gear wheel having their teeth offset angularly half the pitch of the teeth and a tooth fixed on a shaft in the train, and connections from the time mechanism for effecting relative reciprocatory movement between said gear wheel and tooth.

9. A prepayment meter mechanism having coin controlled mechanism and a time mechanism, in combination power line switch controlling means, a meter, a gear train between said meter and switch controlling means, an escapement mechanism in said gear train comprising a double gear wheel having the teeth of said double gear wheel being offset angularly half the pitch of the teeth and a tooth fixed on a shaft in the train, connections from the time mechanism for effecting relative reciprocatory movement between said gear wheel and tooth, a pinion wheel fixed to said double escapement gear wheel, gear connections from said pinion to said switch controlling means included in said

train, and a driving spring and gear connections therefrom to said pinion.

10. A prepayment meter mechanism having coin controlled mechanism and a time mechanism, in combination power line switch controlling means, a meter, a gear train between said meter and switch controlling means, power means for driving said gear train, an escapement mechanism in said gear train comprising a tooth fixed on a shaft in said gear train, and a double gear wheel having the teeth of said double gear wheel being offset angularly half the pitch of the teeth, and means for reciprocating said double gear relatively to said tooth, said means being controlled by the time mechanism.

11. A prepayment meter mechanism having coin controlled mechanism and a time mechanism, in combination power line switch controlling means, a meter, a gear train between said meter and switch controlling means including one sun wheel of a differential and an escapement mechanism, power means for driving said gear train, a time mechanism operating said escapement mechanism, and a gear train actuated from said coin controlled mechanism and including the other sun wheel of said differential for setting said switch controlling means.

12. A prepayment meter mechanism having coin controlled mechanism and a time mechanism, in combination power line switch controlling means, a meter, a gear train between said meter and switch controlling means including one sun wheel of a differential and an escapement mechanism, a time mechanism operating said escapement mechanism, a gear train actuated from said coin controlled mechanism and including the other sun wheel of said differential for setting said switch controlling means, and spring means operating on said gear trains.

13. A prepayment meter mechanism having coin controlled mechanism and a time mechanism, in combination power line switch controlling means, a meter, a gear train between said meter and switch controlling means including one sun wheel of a differential and an escapement mechanism, a time mechanism operating said escapement mechanism, a gear train actuated from said coin controlled mechanism and including the other sun wheel of said differential for setting said switch controlling means and for winding said spring and spring means operating on said gear trains.

PAUL MOOS.
